ROTARY PILOTING APPARATUS

Fritz A. Zander, Ann Arbor, Mich., assignor to Marion E. Abbott, trustee, Ann Arbor, Mich.

Application July 22, 1955, Serial No. 37,104

Term of patent 14 years

(Cl. D26—5)

FIG-1

FIG-2

Figure 1 is a front prospective view of a rotary piloting apparatus, showing my new design; and
Figure 2 is a rear perspective view thereof.

I claim:

The ornamental design for a rotary piloting apparatus, substantially as shown.
